(57) **CLAIM**

The ornamental design for a bicycle pedal, as shown and described.

DESCRIPTION

FIG. 1 is a perspective view of the bicycle pedal;
FIG. 2 is a top view of the bicycle pedal, the bottom view being a mirror image thereof;

FIG. 3 is a front view of the bicycle pedal;

FIG. 4 is a rear view of the bicycle pedal; and,

FIG. 5 is a right side view of the bicycle pedal, the left side being substantially similar thereto.

The broken lines are directed to environment and form no part of the claimed design.
